UNITED STATES PATENT OFFICE.

BENJAMIN E. D. STAFFORD, OF PITTSBURG, PENNSYLVANIA, ASSIGNOR TO FLANNERY BOLT COMPANY, OF PITTSBURG, PENNSYLVANIA.

STAY-BOLT FOR BOILERS.

No. 909,956.

Specification of Letters Patent.

Patented Jan. 19, 1909.

Application filed July 29, 1908. Serial No. 445,899.

To all whom it may concern:

Be it known that I, BENJAMIN E. D. STAFFORD, of Pittsburg, in the county of Allegheny and State of Pennsylvania, have invented certain new and useful Improvements in Stay-Bolts for Boilers; and I do hereby declare the following to be a full, clear, and exact description of the invention, such as will enable others skilled in the art to which it appertains to make and use the same.

My invention relates to an improvement in means for bracing the roof and crown sheets of boiler fire boxes, the object being to provide connections between the crown and roof sheets of boilers, that will allow for, and accommodate the forces of expansion and contraction on lines of least resistance, and that will permit of material movement of the complete fire box under expansion and contraction without imparting twisting or bending strains to the stay rods or the sheets to which the stay rods are attached.

With these objects in view my invention consists in the parts and combinations of parts as will be more fully described and pointed out in the claims.

In the accompanying drawings, Figure 1 is a view in section through roof sheet of boiler and crown sheet of fire box showing my improvement applied thereto. Fig. 2 is a view in elevation of a series of pads showing the manner of arranging them against the inner face of the roof sheet. Fig. 3 is a similar view of a modified form of pad. Fig. 4 is an enlarged view in section of a section of the construction shown in Fig. 1. Fig. 5 is a view of a modified form of pad, and Figs. 6 and 7 are views of modifications.

In staying or bracing the inner and outer sheets of boilers it is at present customary to employ either rigid or flexible stay bolts at the sides, and jointed or sectional braces between the roof and crown sheets. Within the past few years flexible stay bolts, owing to their ability to maintain natural conditions throughout under changeable pressures and temperatures, have practically superseded the rigid bolt at the sides and at some points between the crown and roof sheets, but they have not, owing to the difficulty in applying them, been employed generally between the roof sheet of the boiler and the crown sheet of the fire box.

One of the common forms of stay bolts now in general use is the Tate flexible stay bolt, which comprises a bolt threaded at one end for attachment to the inner sheet and provided with a rounded head the latter resting on a curved seat in a sleeve or bushing, the latter being threaded externally for attachment to the outer sheet of the fire box, and for the attachment of the cap which forms a steam tight joint with the sleeve. 60 This bolt can be readily applied to two sheets that are parallel or nearly so, but it has been found difficult to adapt them to portions of roof sheets, and crown sheets where the sleeves which screw into the curved 70 roof sheet will rest at an angle to the bolt, and my improvement is designed particularly for adapting stay bolts of the type above referred to, to the crown and roof sheets. 65

In the drawing Fig. 1 I have shown the 75 Tate flexible bolt 1 connecting the crown and roof sheets at the sides, and 2 represents the same bolt used in connection with my improved pads or plates 3. These pads are preferably provided with parallel sides 4 80 and pointed ends 5, each end of one resting between the two ends of the next adjacent two. By this arrangement it is possible to have the securing rivets 6 farther removed from the bolt holes than would be possible 85 with pads having square ends, and thus not only solidly secure the pads to the roof sheet, but prevent any material weakening of either the pads or the roof sheet. I prefer to provide each pad with either four 90 seats 7 as shown in Fig. 2, or six seats as shown in Fig. 3, but the number is immaterial as my invention comprehends broadly the pads secured to the inner face of the roof sheet 8 and provided with one or a plurality 95 of seats. These pads 3 may be made of cast steel, compressed steel or drop forging, and each is curved to conform to the inner face of the roof sheet 8, and is secured thereto by a series of rivets 6. Each pad is provided 100 with one or more depressed seats 7 having an opening through its bottom for the passage of the bolts 2. The seats 7 are curved to conform to the contour of the spherical heads 9 of the bolts 2, while the openings 10 105 through the bottom of the seats, are sufficiently large to permit of the necessary movement of the bolt with relation to the roof sheet 8, and are as shown in Fig. 1, arranged in line with the axes of the bolts, 110

The head 9 of each bolt 2, therefore, has a solid bearing in its seat 7 irrespective of its position, the opening in each, being flaring as shown in Figs. 4 and 5 so as to permit of the necessary movements.

The roof sheet 8 of the boiler is provided with a threaded hole for each stay bolt 2. These holes are somewhat larger than the heads of the bolts, and are so formed and 10 threaded that the caps 11 are radial to the roof sheet, and in most instances, (except at the center of the fire box when the bolts are substantially vertical) the caps 11 rest at an angle to the bolts 2 as clearly shown in Fig. 1. The seats 7 in the pads 3 are always in line with the axes of the bolts 2 thereby permitting the ready insertion and withdrawal 15 of the bolts, and the threaded holes in the roof sheets 8 are radial to the latter, and so 20 located with relation to the bolt seats that when the caps 11 are removed, the bolts may be readily removed and replaced. These pads 3 may be drop-forged as shown in Fig. 4 or of pressed steel as shown in 25 Fig. 5, but in each instance they are riveted to the inner face of the roof sheet 8, and are provided with one or a plurality of seats 7 for the spherical heads 9 of the bolts 2, and a bell mouth opening 10 for the passage of 30 the bolt through same, and each seat is closed by the cap 11 screwed into a threaded opening in the roof sheet, and provided with a concaved lower face which forms a bearing for the spherical head of the bolt. This 35 construction of parts embodies all the advantages of the flexible stay bolts now generally employed for bracing the fire box at the sides, and in addition, permits of the use of the bolts at points where the ordinary 40 stay bolt cannot be employed.

The stay bolts 2, are threaded at their inner ends and are screwed into threaded openings in the crown sheet 12 of the fire box and then upset in the usual and well 45 known manner.

In the construction shown in Figs. 6 and 7 I have shown the application of the stay bolts 2 to pressed steel pads 3 strengthened by the bushing 14, the latter being spherical externally to conform to the spherical seat in the pad, and spherical internally to form the seat for the head 9 of the stay bolt 2. By the application of the bushing I produce in effect a large head, and consequently an increased circumferential bearing against the pad, to withstand the stresses 50 on the bolt. Again the use of the bushing permits of the use of bolts having heads that are not spherical, as shown in Fig. 7.

It is evident that many slight changes 60 might be resorted to in the relative arrangement of parts shown and described without departing from the spirit and scope of my invention. Hence I would have it understood 65 that I do not wish to confine myself to the

exact construction shown and described, but consider myself at liberty to make such slight changes and alterations as fairly fall within the spirit and scope of my invention.

Having fully described my invention what 70 I claim as new and desire to secure by Letters-Patent, is:—

1. The combination with inner and outer sheets the outer sheet having threaded openings, of pads secured to the inner face of the 75 outer sheet and provided with recessed seats the latter being open at their bottoms, bolts passing through the seats and having curved heads resting on the seats, the inner ends of the bolts secured to the inner sheets, and 80 caps screwed into the openings in the outer sheet.

2. The combination with inner and outer sheets of a fire box the outer sheet having threaded openings, of pads riveted to the 85 inner face of the outer sheets, each pad being provided with a plurality of recessed seats, bolts passing through said seats and provided with rounded heads resting on the seats, the inner ends of the bolts being secured to the inner sheet, and caps screwed into the threaded openings in the outer sheet.

3. The combination with inner and outer sheets, the outer sheet having threaded openings therein, and pads secured to the inner face of said outer sheet, and provided with recessed seats, of bolts having curved heads resting in said seats, the inner ends of the bolts being secured to the inner sheet, and 95 screw caps secured within the threaded openings in the outer sheet and forming a bearing for the heads of the bolts.

4. In a fire box, the combination with the outer sheet thereof provided with holes, and 105 pads secured to the inner face of said outer sheet, each pad being provided with a plurality of recessed seats, each seat registering with a hole in the outer sheet, of stay bolts passing through the pads with their heads 110 resting in the recessed seats thereof, and closures for the holes in the outer sheet.

5. The combination with inner and outer sheets of a fire box the outer sheet having threaded holes therein, and a series of pads 115 riveted to the inner face of the outer sheet, each pad having a plurality of depressed seats each of which is in alignment with a threaded opening in the outer sheet, of a bolt passing through each seat and having a 120 rounded head resting on the seat and a cap closing the openings in the outer sheet and forming bearings or abutments for the head of the bolt.

6. The combination with inner and outer sheets, the outer sheet having threaded openings therein, of a series of abutting pads riveted to the inner face of the outer sheet each pad having parallel sides and pointed ends, and each provided with a plurality of 130

depressed seats, bolts passing through the seats and provided with rounded heads resting on the latter, the inner ends of said bolts being secured to the inner sheet and screw 5 caps closing the openings in the outer sheets and forming bearings or abutments for the heads of the bolts.

7. The combination with inner and outer sheets, the outer sheet having threaded openings therein, pads secured to the inner face of the outer sheet and provided with recessed seats and a bushing for each seat, the said bushing being shaped externally to conform to the curved surfaces of the seats, of 10 bolts the heads of which rest in said bushings, the inner ends of the bolts being secured to the inner sheet, and caps screwed into the threaded openings in the outer sheet.

8. The combination with inner and outer

sheets, the outer sheet having threaded openings therein, pads secured to the inner face of the outer sheet and provided with recessed seats, and a bushing for each seat, the said bushings being shaped externally to conform to the curved surfaces of the seats 20 and provided with curved seats for the heads of the bolts, of bolts having curved heads resting in said bushings, the inner ends of the bolts being secured to the inner sheet, and caps screwed into the threaded openings 25 in the outer sheet.

In testimony whereof, I have signed the specification in the presence of two subscribing witnesses.
